[57] CLAIM

The ornamental design for a telescopic hand tool extension device, as shown and described.

DESCRIPTION

FIG. 1 is a front elevational view of the telescopic hand tool extension device showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is an exploded side elevational view thereof.

FIGS. 1-4 are shown fragmented to indicate that for ease of illustration a precise length of the article is not claimed.
